UNITED STATES PATENT OFFICE.

JACOB MARVIN ROBERTS, OF NORFOLK, VIRGINIA.

SIGNALING APPARATUS.

1,420,618.

Specification of Letters Patent. Patented June 20, 1922.

Application filed September 22, 1917, Serial No. 192,747. Renewed September 10, 1921. Serial No. 499,862.

To all whom it may concern:

Be it known that I, JACOB MARVIN ROBERTS, a citizen of the United States, residing at Norfolk, in the county of Norfolk and 5 State of Virginia, have invented certain new and useful Improvements in Signaling Apparatus, of which the following is a specification, reference being had therein to the accompanying drawing.

10 This invention relates to signalling apparatus of various sorts. They are typified by messenger call mechanism, police signalling devices, and the like. One of the objects is to provide a signalling apparatus with a motor for actuating the recording devices; which motor will be actuated at each actuation of the device which primarily responds to the remote calling agency, and which will move the record-carrying element properly 15 in relation to the other parts. Another object is to provide an apparatus in which the signal characters of each set will be clearly defined and be properly spaced in relation to the others of a set, and by which each set, as 20 an entirety, will be properly disposed in relation to the succeeding set. Other matters advantageous in such devices are aimed at, as will be set forth below.

Fig. 1 is a side view of an indicator apparatus embodying my improvements.

Fig. 2 is a top plan view.

Fig. 3 is an end view.

Fig. 4 is a view from the side opposite to that in Fig. 1 showing the parts more particularly connected with the improvements, the others being broken away.

Fig. 5 is a vertical transverse section on the line 5-5 of Fig. 1, looking toward the left.

40 Fig. 6 is a vertical section on the line 6-6 of Fig. 2, looking toward the right.

Fig. 7 is a face view with the intermediate frame plate detached.

Fig. 8 is a side view of the train of gear 45 wheels, looking toward the left in Figs. 1 and 2.

Fig. 9 is a view, partly in front elevation and partly in section, of the operative parts shown in Fig. 3.

50 Fig. 10 is a face view of a section of the tape or carrying device for the signal characters.

Fig. 11 is a vertical section of the standard which supports the armature, lever and 55 adjunct parts.

Fig. 12 is a fragmentary view of the bottom part of the powder delivering device, on a relatively larger scale.

Fig. 13 is a fragmentary view showing the spring ratchet wheel and its driving pawl. 60

Fig. 14 is a diagrammatic view illustrating the use of a modified form of motor.

I have shown the device more particularly connected with my invention as applied to a telegraph sounder. The sounder 1 may 65 be of any usual form, the one shown having a base 2, magnets 3, terminals 4 for the mains, the armature lever 5 pivoted at 5^a and having a vibrating end 5^b. Around the end of the armature lever is arranged the frame 70 6-7-8, having the top horizontal arms 6, the outer vertical bar 7, and the inner vertical standard 8, the latter secured at 8^a to the base 2.

The indicator comprises an endless belt 9. 75 It is supported on rollers 10 and 25^a and on a small central table 9^a. Roller 10 has flanges 10^a and teeth or corrugations 10^b for engaging the belt. 11 is a centrally grooved roller on a swinging arm 12 pivoted at 13 and 80 yieldingly held in place by spring 14. 15 is a vertically movable receptacle adapted to hold a material, such as a dry powder, of suitable color. As shown, it has a cylindrical wall 18, a discharge aperture 16, a horizontal screen 17, and a chamber 17^a, immediately above the discharge aperture. It has a cap-closed aperture at 19. It is yieldingly supported by an elastic arm 21, fastened at 22 on the frame, engaging with 85 loop 20.

23 is a brush on shaft 24, with a hub 23^a and tufts 25, this brush removing powder from the belt as it approaches the receiving receptacle 15. 26 is a hood covering the 95 brush. Roller 10 is on shaft 27, carrying pinion 27^a. Roller 25^a is adjacent to brush, and to shaft 28, carrying pinion 29.

Shafts 27 and 28 (respectively advancing the ribbon and rotating the brush) are actuated by devices supported and related as follows:

The frame on the mechanism comprises the front plate 30, the rear plate 31, and an intermediate plate 36. Plates 30 and 31 are 105 braced by spacing tubes 32, 33, 34 and 35, and screws 32^a in the tubes engage the plates. The intermediate frame plate 36 is fastened to plate 31 by spacing tubes 37 and screws 37^a.

This frame supports a series of shafts 38, 39 and 40, as well as the above-mentioned shafts 24, 27 and 28. These shafts are connected by gearing, viz: large wheel 42 on shaft 38, pinion 43 and wheel 44 on shaft 39, pinion 45 and wheel 46 on shaft 40, and pinion 47 and wheel 48 on shaft 24.

49 is a helical spring within a cylindrical casing 49^a. One end is fastened by pin 50 to shaft 38 and the other end fastened by pin 51 to the casing. 52 is a ratchet wheel on the casing 49^a. 65 is a stop lug on the casing 49^a, and 66 is a stop lug on wheel 42, arranged to strike the lug 65.

15 The ratchet 52 is moved by pawl 56 and is locked against retraction by pawl 53, yieldingly held by spring 54. Pawl 56 is carried by a slide 58 comprising a plate 59 mounted in guides 61, 62 and having an 20 elongated tongue 60 extending up far enough to be engaged by the vibrating armature lever 5. When the armature descends the slide plate 58 carries the pawl 56 downward and imparts a movement to the 25 ratchet 52 and winds, to some extent, the spring. 58^a is a return spring for the slide 58.

When the wheel 42 is free to turn under the action of the spring 49 it rotates the pinion 27^a of belt feed roller 10 and also the 30 train of gears comprising pinion 43, wheel 44, pinion 45, wheel 46, pinion 47, wheel 48 and pinion 29, the latter, through shaft 24, causing the brush 23 to rotate.

35 63 is a brake shoe arm fixed on slide 58 and adapted to engage intermittently with a friction disc 64 on shaft 28.

The action of the parts described is as follows:

40 Assume that a signal, in the form of a series of (say two) closings and openings of the circuit through terminals 4 and magnets 3, is given. The armature lever 5 is drawn suddenly downward twice. As the 45 end 5^b swings down it, during the first part of its movement (say $\frac{1}{2}$ inch), pushes down the tongue 60 and the plate 58 with pawl 56 and brake 63, during which first part of its movement the pawl 56 is idle. Just before the swinging end 5^b reaches its lowermost limit it strikes a sharp blow on the top of receptacle 15. This causes a small quantity of powdered material to pass from the receptacle through screen 17 and be 55 deposited upon the upper surface of belt 9. The powder and the belt are contrasted to such an extent in color as to have the powder fully visible. It is preferably deposited as a sharply defined circle.

60 At the instant when the pawl 56, in its downward movement, begins to be active on the ratchet 52 in winding the spring, the brake 63 commences to bear with considerable force on the periphery of the 56 brake disc 64. This results in preventing any

motion of the train of gears (extending from shaft 28 back to shaft 38). This holding of the gear train stationary continues during the time of striking the receptacle and depositing the powder, and during this 70 brief interval (that is, during the last $\frac{1}{16}$ inch or thereabouts of downward travel of pawl 58) the pawl imparts a step of rotary motion to ratchet 52 and winds spring 49 to some extent, advancing the stop 65 away 75 from the stop 66.

As the end 5^b of armature lever 5 swings up plate 58 follows it. Shortly after starting up the plate lifts pawl 56 up to its inactive position and also lifts the brake arm 80 63 off from the disc 64. The gear train is then free to move, commencing with wheel 42. Instantly shaft 27 is rotated, resulting in feeding the tape 9 at a predetermined distance, and during the same instant the brush 85 23 is rapidly rotated, and such particles of coloring matter as are brought forward during this step of movement of the tape are entirely removed from that part of the belt which is approaching the receptacle. These 90 movements continue until the stop 66 on wheel 42 reaches the stop 65 on the casing 49^a of the spring drum, the drum being held by the pawl 53.

In brief, at each down movement of the 95 armature lever 5 a deposit of powder is made on belt 9; and during each up movement of the armature and slide 58 there is a forward movement of the belt. During the latter movement (the upward) the brush 100 23 is removing the powder (of previous index deposits) and making clean that part of the belt which is moving toward the powder receptacle 15.

Fig. 10, at 72, 73, shows two sets of signal 105 characters or indicia. Between each character and the next, of a set, there is a vacant section 74 of the tape. Between each set as an entirety, and the next set as an entirety, there is a longer vacant section 75. 110 The characters of each set are successively formed quickly, each during the downward movement of a rapid reciprocation (which includes a down movement and an up movement) of arm 5. After the down movement, 115 arm 5 and slide 58 start to rise in an up movement. Spring 49 commences to unwind during this up movement and wheel 42 is rotated a short distance; but they (wheel and spring) are arrested or stopped before 120 the wheel 42 reaches the limit of its rotary movement, and each down movement of the pawl 56 does commence quickly after the up movement for each of the indicator characters of a set, excepting the last character of 125 that set. When the end of that up movement of these parts 5, 58, etc., (which occurs after the forming of the last indicator character of a set 72, 73, etc.) has been reached, the armature lever 5, slide 58, pawl 56 and 130

brake 63 are held up a relatively longer time. This results from the fact that the signal wheel in the remote call-box has a predetermined gap in the series of its circuit-closing and opening devices; and this gap causes a relatively long opening of the calling circuit. During this longer period of main circuit opening, armature lever 5 not only rises to its uppermost position (as in Fig. 1), but as before stated, remains in its up position for a long time—long enough to permit spring 49 to move wheel 42 far enough to bring its stop 66 entirely around to stop lug 65. During this longer rotary movement of shaft 27 and tape-feed drum 10, one of the longer sections (75) of the tape is advanced, and the distances between the sets of signals are thus clearly indicated visually.

Consequently, whether there are two deposits of powder in a set of characters, or three, or four, not only will each deposit, considered by itself, be clearly defined on the surface of the belt and distinguishable from each of the others, but each signal set will be suitably spaced from those adjacent.

The train of gearing from wheel 42 to wheel 28 not only provides means for rapidly rotating the brush and thoroughly cleansing the tape, but also means to which the brake 63 can be applied in such a way as to instantly start or stop the spring. These devices for braking are in contradistinction from a brake acting at a point near the spring drum.

The pressure roll 11 bears against the edge parts of the upper surface of the belt, and being centrally grooved (see Fig. 1), will not contact or interfere with the particles of indicator material thereon.

Shaft 27, at its outer end, has a friction disc or pulley 68. With this engages a small brake block 69, carried by a screw 70 supported in bracket 71. This brake can be adjusted, and clamped in position to properly control the travel of the tape.

The tape being longitudinally stationary while the receptacle 15 is being jarred and is dropping a charge of powder, there is no drag on the powder on the tape, and a clear definition of the mark is secured.

The hood 26 is shown as formed with a powder-collecting pocket 26^a, from which the powder can be periodically taken and returned to the receptacle 15.

Varying circumstances necessitate adjusting the pivoting of the armature bar 5. The devices for accomplishing this are shown in Fig. 11. 76, 76 are standards secured to the base 2. 77 is a yoke piece sliding adjustably in the standards 76, and carrying the pivot 5^a for the armature. The yoke 77 should move truly vertically, and it is held by guide pins 78 in grooves 79.

The yoke is moved up or down by arms

80, each of which is pivoted at 81 to one of the legs of the yoke, and at its upper end has a bearing 82. The bearings are supported on a shaft 83, which is mounted in the standards 76. The central part, longitudinally, of the shaft is provided with a cam 86 (held by a fastener 87) which is fitted in the bearings 82. The shaft has a milled disc head 84, which when turned in proper direction causes the cam 86 to draw 75 upward or push downward on the links 80, and they, in turn, move the yoke 77 and the armature pivot 5^a vertically to bring the latter to proper position.

With these devices the blow and thrust 80 of the armature bar 5 can be varied as required to obtain the proper movements of the parts actuated by it.

I prefer to supplement the screen 17 by a finer screen 17^b (Fig. 9) arranged a little 85 below the screen 17, and preferably clamped between the chamber 17^a of the receptacle 18 and the discharge nozzle which is formed with the said aperture 16. This clamping may be by means of small screws 17^c. The 90 upper screen holds back the powder in the main body of the receptacle and prevents it from packing in the chamber 17^a, and just enough powder sifts into said chamber and to the lower screen for a proper marking on 95 the belt 9.

The powder reservoir 18 is slidably mounted on the frame of the machine by a vertical tongue and groove arrangement indicated in dotted lines at 18^a in Fig. 9. 100

In order to prevent the teeth 10^b from carrying the belt under the roller 10 I provide a fixed arm 10^c (Fig. 9) which strips the belt from the roller 10, this arm being one of the plate-securing screws, sufficiently 105 elongated for the purpose.

At the side of the discharge nozzle away from which the belt 9 moves (the left hand side in Fig. 9) I prefer to form a slight cut-out 16^a whereby the deposits of powder are 110 enabled to pass out from under the discharge nozzle without being smeared, in cases where the belt advances before the nozzle or powder outlet rises out of contact with the belt. It will be understood that 115 such construction of the powder outlet enables me to form an elongated mark or deposit of powder, if the belt should be moving.

I have heretofore made signalling devices 120 of this class, in each of which I attach the powder receptacle to the armature lever. But I have found the present construction and arrangement very materially superior. I impart blows to the powder receptacle in 125 contradistinction from giving it mere reciprocatory movements, these blows delivering the powder with greater assurance and accuracy, the mass of powder deposited being sharply defined.

Any suitable powder can be utilized for the indicator marks; and it should be of a color contrasting with that of the tape, so as to be readily visible.

- 5 The parts at 49, 49^a, 42 and 38, may be regarded as a secondary motor (for advancing the tape or equivalent work) which is automatically energized by a primary motor while forming the indicator characters, or 10 equivalent work, the latter motor, as shown, comprising pawl 56, the slide 58, the reciprocating arm 5, and electro-magnetic devices for moving it. In lieu of a primary motor, such as just specified, one of modified form can be used, such as a small electric motor, connected to the spring 49 by gears, equivalent to the pawl 56 and ratchet 52, the circuit through the motor to be closed by devices timed in their actuation, substantially as described, so as to have the receptacle 15 and tape 9 reciprocally and intermittently active and inactive.

Fig. 14 illustrates such an arrangement in which 98 is an electric motor operating 25 through suitable gears 103 to wind up the spring 49 whenever the source of electrical energy flows through the circuit 99 to the motor, this taking place when the slide 58 completes the circuit 99 by engaging the 30 contact 101. It will be understood that the ratchet 52, and its gear 42, are loose on the shaft 38.

In such a case a device like the slide 58 would, during the first part of its movement down, lock the spring-driven gear train, and then, during the latter part of each movement, close the circuit through the spring-winding motor; and vice versa. In either case there is a power-transmitting 35 train which is automatically locked during that part of the cycle of movement of the first motor when the secondary motor is being energized, and which power train is automatically unlocked so as to be operative 40 during another part of said cycle. That is to say, the primary motor locks and unlocks the power-transmitting train of the secondary motor.

There are a number of novel parts of the 50 apparatus which can be utilized with indicators of other sorts, such as perforators or crimpers, in lieu of a powder depositor, together with a traveling body to carry the visible characters so formed, in lieu of the 55 tape or carrier for the powder-deposits here presented.

I do not however present herein claims 60 specifically relating to these devices for producing permanent visual characters upon the tape, or its equivalent, I having presented claims relating thereto in another application No. 565,206 filed June 1, 1922; nor do I herein claim the specific features of construction, relative arrangement and mode of operation incident to the prime lever, the mag-

nets, the spring, the gearing, the brake and the other devices presented in said other application wherein I have illustrated and described several improvements to which I have been led by my experience with the 70 form of mechanism herein described.

What I claim is:—

1. In a signalling apparatus, the combination of a primary motor, a primary power transmitter, a secondary motor energized by 75 said primary power transmitter, a secondary power transmitter, a signal receiving and carrying device which is moved by said secondary power transmitter, means actuated by said primary motor for producing signals 80 on said signal receiving device, and means actuated by the primary motor for preventing transmission of power by said secondary motor.

2. In a signalling apparatus, the combination of an armature, a slide and pawl actuated by said armature, a spring which is wound and energized by said slide and pawl, a train of gearing actuated by said spring, a tape adapted to receive and carry signals, 90 and a brake actuated from said armature for preventing the expansion of said spring.

3. In a signaling apparatus, the combination of the powder depositor, the movable deposit receiver, the shaft for moving the receiver, the spring having one end fixed relatively to the shaft, means for winding the spring, a power transmitter which actuates the depositor and simultaneously winds the spring and locks it against action and is also 100 adapted to free the spring and permit it to rotate said shaft.

4. In a signaling apparatus, the combination with the powder depositor of a movable deposit receiver, the motor spring having 105 one end fixed relatively to the deposit receiver, means connected to the other end of the spring for winding it, a reciprocating power transmitter which, while moving in one direction, actuates the powder depositor 110 and also winds the spring and locks it, and while moving in the other direction frees the spring to permit its advancing the deposit receiver.

5. In a signaling apparatus, the combination of the powder depositor, the movable deposit receiver, the shaft for moving the receiver, the spring having one end made stationary relatively to the shaft, means connected with the other end of the spring for 120 winding it, two inter-engaging stops, one connected to the shaft and one connected to the spring winder, the power transmitter which actuates the depositor and moves one end of the spring in the winding direction, 125 and automatically acting means for preventing the spring from moving in the unwinding direction while the depositor is acting.

6. In a signaling apparatus, the combination of the powder depositor, the movable 130

deposit receiver, the shaft for moving the receiver, the spring having one end made stationary relatively to the shaft, means connected with the other end of the spring for winding it, two inter-engaging stops, one connected to the shaft and one connected to the winder, a reciprocating power device which, through one of its movements, causes the depositor to deliver powder deposits to the receiver and to move one end of the spring in the winding direction, and automatic means for stopping the other end of the spring from moving in the unwinding direction, said reciprocating power device 15 during its opposite movement releasing the spring for either of several limited movements.

7. In a signaling apparatus, the combination with the powder depositor, of the movable deposit receiver, the motor spring adapted to move the deposit receiver, the shaft rotated by and connected to the spring, the ratchet wheel, the drum connected to the spring and having a stop lug, the wheel secured to the 20 shaft, and the stop on the wheel adapted to engage the said stop lug to limit the movement of the deposit receiver.

8. In a signaling apparatus, the combination with the powder depositor, of the movable deposit receiver, the shaft for moving the receiver, the spring at one end connected to the shaft, the drum connected to the other end of the spring, a stop lug on the drum, the inter-engaging stop connected to the shaft, 25 and means for simultaneously winding the spring.

9. In a signaling apparatus, the combination with the powder depositor and the deposit receiver, of means for moving the receiver either a relatively short distance or a relatively longer distance, means for stopping the movement of the receiver at the end of a relatively short movement, and supplemental means for stopping the receiver at the 35 end of a relatively longer movement.

10. In a signaling apparatus, the combination with the powder depositor, of the traveling device which receives and exhibits

the signal-characters so formed, the power device, and means actuated by the power device for imparting blows to the device which forms the signal-characters.

11. In a signaling apparatus, the combination of a powder depositor, movable means for receiving the powder deposits, a power device, and means actuated by the power device for imparting blows to the depositor.

12. In a signaling apparatus, the combination of the powder depositor, means for receiving and exhibiting the powder deposits, 60 the primary motor, the device actuated by the primary motor for imparting blows to the depositor, and means brought into action by the primary motor for moving the deposit receiver after the deposits have been respectively formed thereon.

13. In a signaling apparatus, the combination of the powder depositor, the movable deposit receiver, means for moving the receiver, a reciprocating bar adapted to impart jars to the powder depositor and to cause the actuation of the receiver-moving means after the depositor has been jarred.

14. In a signaling apparatus, the combination of the means for forming powder deposits, the feeding roll for the carrier, and the opposing pressure roll formed with a central groove.

15. In a signaling apparatus, the combination of a deposit carrier, the powder depositor yieldingly supported adjacent to the carrier, and means for striking blows on the depositor.

16. In a signaling apparatus, the combination with the powder depositor and the movable deposit receiver, of an electro-magnetically actuated hammer-like device for imparting blows to the depositor.

In testimony whereof, I affix my signature, in presence of three witnesses.

JACOB MARVIN ROBERTS.
